UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

RADIO RECEIVING SYSTEM.

Application filed November 21, 1922. Serial No. 602,453.

My present invention relates to radio receiving systems and more particularly to systems for obtaining a high degree of selectivity in reception.

For the purpose of eliminating interference from stations and static it is now recognized that highly directive antennæ are especially effective. While sharply directive receiving antennæ have been constructed employing a single loop, a combination of two loops or of a loop and a vertical antenna and a long horizontal antenna of the type now known in the art as the "wave antenna", it is found in practice that there is a limit to the directivity which may economically be obtained with any of these arrangements.

One of the objects of my invention is to provide a receiving system made up of a plurality of receiving units which are connected to one another and to a receiving station in such a way that sharper directivity in reception may be obtained than can be obtained with previously employed systems.

Another object of my invention is to provide a maximum of directivity with a minimum number of units.

Still another object of my invention is to provide a receiving system which will permit of highly directive reception upon a single antenna system from a plurality of transmitting stations located in directions between which there may be a considerable angle.

In carrying my invention into effect I may to advantage employ a plurality of wave antennæ of the type described in Beverage Patent 1,381,089, June 7, 1921, although other forms of directive antenna units may be employed as will appear from the description which follows. It is well known that if a wave antenna is so constructed that the current flows therein at a velocity equal to the velocity of light the maximum signal reception will be in the direction of the antenna. By suitably loading a wave antenna by series condensers or shunt inductances or both the effective wave velocity of the antenna can be made to exceed the velocity of light and may even be made infinite if all of the series inductance is tuned out by series condensers and all of the shunt capacity is tuned out by shunt inductances.

If a signal comes from an angle θ to the direction of the antenna the point of maximum induced electromotive force moves along the antenna with a velocity $\frac{v}{\cos \theta}$ and for maximum signal the wave velocity on the antenna should also equal $\frac{v}{\cos \theta}$. If it is desired to receive signals from a direction at right angles to the antenna this condition requires a line of infinite wave velocity. Reception obtained in this manner either by means of a wave antenna or by equivalent means I term broadside reception, while reception from the direction of the antenna I term end on reception.

The wave antenna when employed either as an end on or a broadside receiver may be considered as made up of an infinite number of receiving elements of infinitesimal size, which in the case of waves coming from the direction of the desired signals deliver the energy which they collect, in such phase at the receiver as to give full amplitude addition. This fine subdivision and distribution of energy collecting elements however is not essential, as a comparatively small number of larger units properly spaced will give substantially the same directive properties. For example, a row of four antennæ spaced a quarter wave length apart gives practically the same directive curve as an infinite number of small antennæ distributed over a wave length. The number of units multiplied by the spacing gives the length of the equivalent wave antennæ and the equivalence is very close provided the spacing does not exceed a quarter wave length in the case of an end on row, and a half wave length in the case of a broadside row. The use of a plurality of units whether each of them is itself directive or not permits however, of greater flexibility in the adjustment of the receiving system for reception from different directions.

The novel features which I believe to be characteristic of my invention are set forth with particularity in the appended claims. My invention itself however both as to its organization and method of operation together with the manner in which the various objects

thereof may be obtained will best be understood by reference to the following description taken in connection with the accompanying drawing in which Fig. 1 is a diagrammatic representation of a complete receiving system adapted for multiplex reception; Fig. 2 shows a slight modification in the receiving system; Figs. 3 and 6 to 9 inclusive are illustrative diagrams of multiple unit combinations; and Figs. 4, 5 and 10 are directive curves illustrative of some of the capabilities of my invention.

The methods to be employed in utilizing a row or group of separate antenna units will depend upon the type of units and their arrangement with respect to the direction or directions from which signals are to be received. In general, to obtain the greatest flexibility of operation, a separate balanced metallic transmission line would preferably be employed for transmitting the energy received by each unit to the receiving station, although in some cases a single transmission line may be used for several antennæ.

At the receiving station means should be provided for combining the signals received from the several units in a single circuit either by a magnetic coupling between each of the transmission lines and the combining circuit or by some equivalent means. Provision should also preferably be made for adjusting both the phase and intensity of the signals from each antenna as they are impressed upon the combining circuit. Phase adjustments may be made by off tuning, by means of a rotating magnetic field provided by a split phase circuit or by means of artificial transmission lines of variable length. The last mentioned method has the advantage that in most systems the same adjustment is correct for all wave lengths or at least for a considerable band of wave lengths providing the proper polarity of transformers is observed. In some cases the desired phase adjustment may be obtained by proper proportioning of the lengths of the transmission lines.

In any multiple unit receiving system or in any receiving system in which signal frequency currents are transmitted for considerable distances care will be needed to prevent undesired electromotive forces or currents from entering and preventing the system from functioning as intended. The following are some of the precautions which may be found desirable.

1. Electrostatic shielding between primaries and secondaries of transformers, particularly of transformers used to connect transmission lines to antennæ.

2. The use of iron core transformers or of astatic air core transformers to reduce undesired magnetic couplings.

3. Careful balancing and transposition of transmission lines and balancing of all trans-

formers or coils connected thereto which have connections to neutral points of their windings.

4. Damping of transmission lines by resistance to prevent reflections and standing wave effects.

5. Fitting of impedances between transmission lines and artificial lines or other apparatus to which the transmission lines are connected.

6. Prevention of excessive voltages building up on transmission lines by wave antenna action. This may involve draining off of foreign currents from the neutral points of drain coils or of balanced transformer windings, or the loading or sectionalizing of the transmission lines in such a way as to reduce their action as antennæ without materially impairing their efficiency as transmission lines.

7. Providing grounding connections for shields and drains separate from the grounds used for antennæ, in order that foreign currents passing through a common ground resistance may not cause harmful voltages in the antenna circuit.

8. Electrostatic and electromagnetic shielding of interior circuits to prevent all undesired mutual reactions.

In accordance with the facts already set forth a light velocity end-on wave antenna of length L might be replaced by a row of n static antennæ spaced a distance $\frac{L}{n}$ apart pro-

vided $\frac{L}{n}$ is less than a quarter wave length, each antenna being connected to the receiving station by a transmission line and the lengths of these lines differing in electrical length progressively by a distance $\frac{L}{n}$. Simi-

larly a broadside infinite velocity wave antenna of length L might be replaced by a row of n static antennæ separated by a distance L/n , provided L/n does not exceed a half wave length. The transmission lines in this case should all have the same electrical length.

In case it is not convenient to build lines having a geographical length corresponding to the desired electrical length the electrical length may be made greater or less than the geographical length by suitable loading or by the addition of a suitable artificial line. If all of the antennæ in the row or group were static antennæ which receive equally from all directions the system would have a certain directive curve, characteristic of the location and spacing of the units, the wave length received, and the electrical length of the transmission lines. We may call this the "group

directive curve" and designate it by "A". If now the static antennæ are replaced by antennæ which individually have a directive curve "B", then the system as a whole will

have a directive curve which is the product of A and B. That is to say the radius of the product curve for a given direction is the product of the radii of A and B for the same direction. This product rule is of great assistance in the design of any multiple unit system. By making the "blind" or low intensity directions of the group curve "A" come where curve "B" taken by itself would give undesirable reception, and vice versa, a product curve may be obtained with a number of "blind spots" and with very slight reception over a wide range of direction.

The theory of the product principle may be illustrated by the case of two loop-and-vertical, cardioid units, placed a half wave length apart, and equally distant from the source of the desired signal and connected to the receiving station by transmission lines of equal length, as indicated in Fig. 3. First to find curve A, we determine the directive properties for two static antennæ placed as described. For $\theta=0$, or the direction of the desired signal, the space wave strikes the two antennæ simultaneously, and since the transmission lines are of equal length, we have zero phase difference and full addition of the two currents in the receiver. For $\theta=30^\circ$, the space wave will reach one antenna a quarter wave length before it reaches the other. Then the currents at the receiver will add in quadrature, giving an intensity 1.41 times that from either antenna alone. For $\theta=90^\circ$, the space wave will reach one antenna a half wave length before the other, and the currents at the receiver will be in direct opposition, giving zero reception. The intensities for $\theta=0^\circ$, 30° , and 90° are therefore in the ratio 2, 1.41 and 0. For $\theta=150^\circ$, we again have quadrature addition, and an intensity 1.41 and for $\theta=180^\circ$, we have an intensity 2.00.

A single cardioid unit gives the following intensities:

Angle θ°	Relative Intensity
0	1.00
30	.933
90	.50
150	.066
180	.00

With the two cardioid units spaced as in Fig. 3, we will have the following receiver currents—

For $\theta=0$, two currents of intensity 1.00 each, in full addition, giving a receiver current of intensity 2.00.

$\theta=30^\circ$, two currents of intensity .933 in quadrature giving a receiver current $1.41 \times .933 = 1.31$.

$\theta=90^\circ$, two currents of intensity .50 in direct opposition giving zero resultant in the receiver.

$\theta=150^\circ$, two currents of intensity .066, in quadrature giving a resultant $1.41 \times .066 = .093$.

$\theta=180^\circ$, no current from either antenna. Putting the above in tabular form

θ°	Directive curve for two static antennæ	Cardioid single unit	Directive curve for two cardioid units
0	2.00	1.00	$2.0 \times 1.0 = 2.00$
30	1.41	.933	$1.41 \times .933 = 1.31$
90	0	.50	$0 \times .50 = 0.0$
150	1.41	.066	$1.41 \times .066 = .093$
180	2.00	0	$2.0 \times .00 = 0.0$

Fig. 4 shows the shape of the curve A for the two static antennæ, the curve B of the cardioid unit, and the product or curve for the combination. In this, curve A has been reduced to the basis of unit intensity for $\theta=0$.

A pair of spaced loops is another application of the product principle. Two static antennæ spaced a quarter wave length apart in the direction of the signal, and with one transmission line a quarter wave length longer than the other, give a cardioid directive curve. With the static antennæ replaced by loops pointed in the direction of the signal, the system gives a directive curve which is the product of the cardioid just mentioned and the figure eight which is the directive curve of a loop. The quarter wave length spacing of the loops is not essential, but is the simplest case to discuss.

A pair of broadside wave antennæ is another application. In this case the cardioid, corresponding to two units a quarter wave length apart in the direction of signal travel, is multiplied by the very sharp figure eight curve of the broadside wave antenna.

The product principle may be extended to groups of groups or rows of rows. One such application is of especial importance. In order to obtain a very sharp directive curve, using a broadside row of units, we extend the row. This sharpens the main lobe of the curve, but smaller lobes appear on the sides as shown in Fig. 5. It is evident that we might obtain a sharp main lobe without any side lobes, if we could take the curve A Fig. 4 for a broadside pair of static antennæ a half wave length apart, and square or cube all its radii. To lay out a system which will give a directive curve which is the square of A Fig. 4, we would need to use two pairs of units, each pair of which would give A of Fig. 4 and then treat each of these pairs as a unit of a big pair using the same spacing, as shown in Fig. 6. This puts the center of the second pair a half wave length from that of the first pair, which brings two of the antennæ into coincidence. All of the transmission lines have the same electrical length, so a single unit at the center giving double intensity may be used in place of the two. Thus

a broadside row of three antennæ spaced a half wave length and having intensities in the ratio 1:2:1 will give the directive curve C of Fig. 10, whose radii are the squares of those of A of Figs. 4 and 10. Let us carry the process one step farther, and combine two of the 1:2:1 groups just described into a broadside pair spaced a half wave length center to center of group. This gives

10	Group I	1:2:1
	Group II	1:2:1
15	Total system	1:3:3:1

Again there are antennæ coinciding, so that in effect we simply add an antenna on one end of the row and increase the relative intensity of the two middle units to three times that of the end units. Such a system gives the directive curve D of Fig. 10 which is the product of A of Figs. 4 and 10 and C of Fig. 10 or the cube of curve A of Figs. 4 and 10. Carrying the process one step further gives a broadside row of five antennæ spaced a half wave length, and having intensities in the ratio 1:4:6:4:1. This gives the directive curve E of Fig. 10, which is curve D of Fig. 10 multiplied by A of Fig. 10, or the square of curve C of Fig. 10. The product principle makes it a simple matter to calculate the directive curve of a field covered with antennæ in square formation for this may be considered as a broadside row of end-on rows or vice versa.

In order to obtain advantage from changing the intensity of certain of the units in a multiple unit receiving system, it is not necessary to adhere to the exact arrangement of values just described, changing the intensity of the units near the middle of a broadside row as compared with that of the end units, is a means of altering the directions from which there is zero reception. For example, three units in a broadside row spaced a half wave-length apart, and with equal intensities give zero reception 42° from the normal signal direction (perpendicular to the row of units). Reducing the intensity of the middle unit brings the angle of zero reception closer to the signal direction but permits stronger reception from directions nearly parallel to the row. If the intensity of the middle unit is reduced to zero the angle of zero reception is 30° from the signal direction but the remaining units give full addition for disturbances coming at right angles to the signal or parallel to the row. On the other hand, if the intensity of the middle unit is greater than that of each of the end units the reception from a direction at right angles to the signal is reduced, and the angle of zero reception is more than 42° from the signal direction, reaching 90° when the intensity of the middle unit is twice that of either end unit. With other

spacings or other numbers of units the directions of zero reception can be similarly controlled by varying the intensities of the units near the middle of the row as compared with that of the end units.

Any multiple unit system, in which the phase of the currents from the several units can be adjusted in the station, may be warped, or the direction of maximum reception shifted. This is done by shortening the electrical lengths of the transmission lines from the units farthest from the source of signals (or advancing the phase of the currents from these units) and increasing the electrical lengths of the lines from the units that are nearer the source of the desired signals. Thus in the case of a broadside pair, the transmission lines should have equal length to give maximum reception for signals coming at $\theta=0^\circ$ or right angles to the line connecting the two antennæ, but to warp the curve 30° to the right (i. e. to obtain maximum reception for signals from the direction $\theta=30^\circ$ right) we must lengthen the line from the right hand unit or shorten that from the left hand unit, or both so as to make the difference in their electrical lengths equal to one half the distance between the units ($\sin 30^\circ=.5$). How far the warping may be carried satisfactorily depends on the directive properties of the individual units, for obviously no adjustments of relative phase can secure good reception from directions for which the units themselves are inefficient. Therefore, if warping is to be carried very far, it is desirable to have the unit antennæ also adjustable in order that their directions of maximum reception may be shifted at the same time. For example, if the antennæ are loops and it is desired to carry warping more than about 30° , it should be possible to turn the loops, or to obtain the equivalent effect by means of crossed loops and goniometers. Or if the system consists of a broadside row of wave antennæ and warping through a wide angle is necessary, it would be desirable to substitute for the wave antennæ end-on rows of static antennæ or of crossed loops with goniometers.

The advantage gained by warping the directive curve of a multiple unit receiving system is not limited to increasing the signal intensity from stations not located directly in line with the antenna system, but the warping may be used to prevent reception of static or interference from certain directions. Most sharply directive systems have certain directions for which the reception is zero and if disturbances come from a definite direction they may frequently be eliminated by so adjusting the system as to cause one of these directions of zero reception to coincide with the direction of the disturbance. The adjustments described above for warping, not only shift the direction of maximum reception but

70

75

80

85

90

95

100

105

110

115

120

125

130

also shift the direction of zero reception. For example, if a source of disturbance is at an angle of 20° from the desired transmitting station, whereas the unwarped receiving system gives zero reception at 30° from the direction of the desired signal, the system may be warped away from the direction of the disturbance sufficiently to reduce the disturbance to negligible magnitude, while only slightly 10 reducing the intensity of the desired signal.

As an illustration of a complete receiving system adapted for multiplex reception in which the principles above set forth may be employed I have indicated in Fig. 1 three 15 parallel wave antennæ numbered 1, 2 and 3, each of which may point in the general direction of the signals which are to be received. The ends B_1 , B_2 , B_3 of these antennæ are provided with the usual reflection transformers 20 R_1 , R_2 , R_3 , to utilize the antenna wires as a transmission line to transmit to the receiving station signals traveling in the direction from A_1 to B_1 or to transmit to the receiving station over the antennæ as a transmission line 25 desired balancing or neutralizing currents. At the ends A_1 and A_3 I have indicated transformers T_1 , T_3 and S_1 , S_3 for supplying signaling and compensating currents to the balanced transmission lines L_1 , L_3 and M_1 , M_3 , 30 by means of which the desired currents are transmitted to the receiving station. By way of modification I have indicated in antenna No. 2 a reflection transformer R_4 at end A_2 and have provided transformers T_2 and S_2 , 35 connected at an intermediate point in the antenna to the transmission lines L_2 and M_2 .

In the receiving station there may be provided for each antenna artificial lines N_1 , N_2 , N_3 , O_1 , O_2 , O_3 or other time or phase adjusting circuits to which the currents conveyed 40 over the transmission lines may be supplied by transformers 4, 5, 6, 7, 8 and 9. To provide intensity adjustments the currents from the artificial lines are supplied through potentiometers 11, 12, 13, 14, 15, 16, to the control circuits of the coupling tubes 1—S, 1—N, 45 2—S, 2—N, 3—S and 3—N.

The output circuits of these coupling tubes are connected in parallel to the primary 50 of transformer 17, the secondary of which supplies signaling current to suitably tuned receiving circuits and receiving apparatus of any desired type. For testing and adjusting purposes suitable switching arrangements 55 should be provided to permit any one or more of the plate circuits of the coupling tubes to supply current to the receiving apparatus to the exclusion of other tubes. It will be understood that the vacuum tubes indicated 60 will be connected in the usual manner, part of the connections having been omitted from the drawing for the purpose of simplification.

In adjusting the system described to obtain the desired results the sliding connections 65 18, 19, 20, 21, 22 and 23 and the inten-

sity couplers 11, 12, 13, 14, 15 and 16 are first adjusted to give the best signal reception. This may be done by adjusting first with one antenna unit at a time connected to the receiving apparatus, then with two units and 70 finally with all three units. In this way an adjustment may be made so that the signaling currents received upon the three antenna units will all add in phase in receiving apparatus and if the currents supplied by the different antennæ are all of the same intensity the maximum signaling currents will be of three times the amplitude of the current supplied by single antenna units. The product principle which I have described above applies to the system which I have described and a sharper directivity in reception will be obtained than with a single unit. It may however, be found that when the system is thus adjusted for maximum intensity, interference will be present from a direction between 60° , and 120° from that of the desired signals. With certain antenna spacings this interference may be largely eliminated by readjusting the intensity couplers so that the 80 intensity of the currents received from antenna 2 and impressed upon the receiving apparatus differs from that of the currents received and impressed upon the receiving apparatus from antennæ 1 and 3 respectively. 85

While I have indicated in Fig. 1 the complete apparatus for receiving only one message I have indicated additional potentiometers or intensity couplers 24, 25, 26, 27, 28 and 29 and 31, 32, 33, 34, 35, 36 with sliding 90 contacts between the intensity couplers and the artificial lines. These may be connected to additional sets of coupling tubes and receiving apparatus so that as many different messages as desired all coming from the same 95 direction or from different directions may be received from a single antenna system.

It will be noticed that in Fig. 1 the arrangement for impressing signals coming in the direction from A_1 to B_1 on the control element 110 of the coupling tube 1—S is essentially the same as that by which signals coming in the direction from B_1 to A_1 are impressed on the control element of coupling tube 1—N. For the present the discussion will be confined to 115 antenna No. 1, the coupling tubes 2—S, 2—N, 3—S and 3—N being considered inactive. If the desired signal has the direction A_1 to B_1 , it will be received almost entirely through the coupling tube 1—S, and the desirable adjustment of the potentiometer 11 will be one which impresses the total available potential on the control element of the 120 coupling tube 1—S. If at the same time there is a disturbance coming in the direction B_1 — A_1 , this impresses a relatively small voltage on the potentiometer 11 and a much larger voltage on the potentiometer 14. But by adjusting potentiometer 14 so that only a 125 fraction of the available voltage across the 130

potentiometer is impressed upon the coupling tube control element, the voltage supplied to the control element of coupling tube 1—N due to the disturbance, may be made equal 5 to the voltage which the same disturbance causes to be impressed on the control element of coupling tube 1—S. The voltages impressed on the control elements of coupling tubes 1—S and 1—N as a result of the disturbance, may then be brought into phase opposition by adjustment of the sliding contact 21 on the artificial line O₁. All effect of the disturbance coming in the direction B₁—A₁ will then disappear from the receiving set, 10 since the voltages impressed on the control elements of 1—S and 1—N are equal and opposite and the signal frequency anode currents will neutralize. The desired signal causes only a relatively small voltage to be 15 impressed on the potentiometer 14 and since only a small fraction of this voltage is applied to the control element of the coupling tube 1—N, there is practically none of the desired signal current in the anode circuit of 20 control tube 1—N, and the adjustment of potentiometer 14 and phase adjustment 21, do not impair the strength of the desired signal which is supplied to the receiving set 25 through coupling tube 1—S.

30 It is evident from the symmetrical arrangement, that by means of a different set of adjustments of the potentiometers 11 and 14 and of the sliding contacts 18 and 21 which adjust phase, the receiving set may be made 35 to receive with full intensity desired signals coming in the direction B₁—A₁, while undesired signals or disturbances coming in the direction A₁—B₁, are neutralized in the receiving set. In other words the unidirectional properties of the antenna may be 40 reversed. Since the system shown in Fig. 1 provides for a number of receiving sets, and the adjustments of these sets are mutually 45 independent, it is possible to obtain unidirectional reception with one receiving set, for signals coming in the direction A₁—B₁, and at the same time to receive signals coming in the direction B₁—A₁, on another receiving set, to the exclusion of signals or disturbances coming in the direction A₁—B₁. 50 The same is true of the entire system of three antennæ, since each antenna can be adjusted in the same way.

If one of the signals to be received on the 55 multiplex system shown in Fig. 1 comes from such an angle that the signal wave does not reach the three antennæ simultaneously, it will usually be desirable to warp the system, thereby giving it a directive curve which 60 points toward the desired sending station. If for example the desired signal reaches antenna No. 3 first and is to be received by receiving set No. 1, the warping will be accomplished by retarding the phase of the voltages received from antenna No. 3 by mov-

ing the sliding contacts 20 and 23 to the right, and advancing the phase of the voltages received from antenna No. 1 by moving the contacts 18 and 21 to the left. In this manner the compensation or unidirectional adjustment of each antenna taken by itself may be kept the same but the phase of the signal currents in the receiving set from the three antennæ may be brought into coincidence thus giving full signal addition. This warping of 70 the directive properties of the system for receiving a particular station on receiving set No. 1, has no effect on the adjustments for the remaining sets. Thus it is possible at the same time to be receiving on set No. 2 another station which calls for warping in the other direction, or advancing the phase of the voltages received from antenna No. 3 and retarding the phase of the voltages received from antenna No. 1, while sets No. 3 and No. 85 4 may be using the system unwarped.

Warping may be used either to increase the signal intensity from stations not directly in line with the system, or it may be used to reduce interference or static coming from 90 certain quarters.

By a modification of the arrangement shown in Fig. 1, the adjustments for warping, and for weighting the antennæ or varying their relative intensities can be performed 95 without disturbing the unidirectional adjustments of the individual antennæ. This modification consists in combining the anode currents of coupling tubes 1—S and 1—N directly as in Fig. 1 and similarly combining the anode currents of 2—S and 2—N, and of 3—S and 3—N, thus producing three currents each from an adjusted antenna, and then combining these three currents through 100 devices by which their relative phase and 105 intensity can be adjusted.

In Fig. 2 I have indicated a slight modification of the system shown in Fig. 1 consisting in the use of variable coupling transformers 40 and 41 which may be moved along 110 the artificial lines to adjust the phase and moved closer or farther from the lines to adjust the intensity of the currents impressed upon the input circuits of the coupling tubes.

In Fig. 1, I have shown a broadside receiving system consisting of three wave antennæ. Fig. 7 shows a broadside receiving system consisting of three static antennæ and three loops with transmission lines leading to the receiving station where 120 the current from each loop may be combined with that from the corresponding static antenna in such a way as to form a unidirectional unit. The currents from the three unidirectional units may then be combined to 125 obtain the sharp directive properties characteristic of the broadside row. Fig. 8 shows a similar arrangement in which each of the three unidirectional units is obtained by combining two static antennæ spaced an appre- 130

ciable fraction of a wave length apart in the direction of signal propagation. Fig. 9 shows an arrangement similar to that of Fig. 8 except that the static antennæ of Fig. 8 are replaced by loops, the loops having the advantage of immunity from disturbances coming from the side. With stationary loops the arrangement shown in Fig. 9 cannot be warped as far to the side as that shown in Fig. 8, because the loops themselves are directive. If, however, the loops are so constructed that they can be turned so as to point in any desired direction, then Fig. 9 permits as much freedom in warping as Fig. 8 while at the same time giving higher directivity. Instead of turning the loops in the field, the same result can be obtained by means of crossed loops and goniometers of the Bellini Tosi type. The goniometers may be located in the receiving station if a separate transmission line is provided from each loop.

While I have shown antenna systems made up of certain types of directional units arranged in broadside rows it will be understood in accordance with the principles set forth that any other form of directional unit may equally well be employed and that as many units as desired may be used without departing from the scope of my invention as set forth in the appended claims.

What I claim as new and desire to secure by Letters Patent of the United States, is:

1. The combination in a radio receiving system of three or more parallel unidirectional receiving antennæ, each having a length as great as a wave length of the signal to be received, separated from one another by a substantial fraction of a wave length of the signals to be received, a receiving apparatus, means for combining the currents received upon the different antennæ in the receiving apparatus and means for varying the intensity and phase of the currents impressed upon the receiving apparatus from the different antennæ so as to impress upon the receiving apparatus currents of different intensity from the intermediate antenna or antennæ than from the outside antennæ.

2. The combination in a radio receiving system of three or more parallel horizontal antennæ separated from one another by a substantial fraction of a wave length of the signals to be received, each having a length as great as a wave length of the signal to be received, a receiving apparatus, means for combining the currents received upon the different antennæ in the receiving apparatus and means for varying the intensity and phase of the currents impressed upon the receiving apparatus from the different antennæ so as to impress upon the receiving apparatus currents of different intensity and phase from the intermediate antenna or antennæ than from the outside antennæ in such a manner

as to vary at will the direction from which reception is obtained.

3. The method of operating a radio receiving system comprising a plurality of directive receiving units and a plurality of receiving sets which consists in selecting from each of said receiving units and impressing upon one of the receiving sets a current of a desired phase and intensity and simultaneously selecting from each of said receiving units and impressing upon another of said receiving sets a current received from a different source having a different carrier frequency than that of the first mentioned current.

4. The method of operating a radio receiving system comprising a plurality of directive receiving units and a plurality of receiving sets which consists in independently selecting from each receiving unit a plurality of currents derived from different sources having different carrier frequencies, combining in each receiving set the currents from a single source which have been selected from the different receiving units and adjusting the phases of the combined currents to produce the desired signal reception.

5. The method of operating a radio receiving system comprising a plurality of directive receiving units and a plurality of receiving sets which consists in independently selecting from each receiving unit a plurality of currents derived from different sources having different carrier frequencies, combining in each receiving set the currents from a single source which have been selected from the different receiving units and adjusting the phases and intensities of the combined currents to produce reception of the desired signal and eliminate interference from waves arriving from other directions than that of the desired signal.

6. The combination in a radio receiving system of a plurality of directive receiving units, a plurality of sets of receiving apparatus, means for impressing upon each receiving apparatus currents derived from each of the receiving units and independent means associated with each receiving unit for separately adjusting the phase and intensity of the different currents impressed therefrom upon the different receiving sets.

7. The combination in a radio receiving system of a plurality of directive receiving units, a plurality of sets of receiving apparatus, an artificial line associated with each receiving unit, means associated with each artificial line for simultaneously selecting a plurality of currents derived from different transmitting sources, means for impressing upon each receiving set currents derived from a single transmitting source and selected from the different receiving units and means for adjusting the phase and intensity of the cur-

rents thus impressed upon each receiving set.

8. The combination in a radio receiving system of a plurality of directive receiving units, a receiving set and means for impressing upon the receiving set currents derived from the different receiving units, said means comprising a plurality of coupling tubes having their output circuits connected in parallel and associated with the receiving sets and 10 their control circuits connected individually to the different receiving units.

9. The combination in a radio receiving system of a plurality of directive receiving units, a receiving set and means for impressing 15 upon the receiving set currents derived from the different receiving units, said means comprising a plurality of coupling tubes having their output circuits connected in parallel and associated with the receiving sets and 20 their control circuits connected individually to the different receiving units, the control circuits of some of the tubes having impressed thereon desired signaling currents and the control circuits of other tubes having impressed thereon currents of the proper phase and intensity to eliminate interference with the desired reception.

10. The combination in a radio directive receiving system of a plurality of rows of 30 receiving antennae each row consisting of a plurality of units separated from each other in the direction of desired signals by a substantial fraction of a wave length and said rows being separated from each other in a 35 direction substantially at right angles to the signal direction by a substantial fraction of a wave length of the signals to be received, a receiving apparatus, balanced transmission lines connecting each antenna unit with the 40 receiving apparatus, and means at the receiving apparatus for adjusting the phase and intensity of the currents impressed from each transmission line upon the receiving apparatus.

45 11. The combination in a radio receiving system of a row of more than two directive receiving units separated from one another by a substantial fraction of a wave length, means for changing the directive curve of 50 each of said units and transmission lines connecting each of said units to a receiving station.

12. The combination in a radio receiving system of a plurality of rows of directive receiving units, the rows being separated from one another by a substantial fraction of a wave length and the units of each row being also separated from one another by a substantial fraction of a wave length and means for changing the directive curve of each unit. 60

13. The combination in a radio receiving system of a plurality of rows of directive receiving units, the rows being separated from one another by a substantial fraction of a wave length and the units of each row being 65 also separated from one another by a substantial fraction of a wave length, means for changing the directive curve of each unit and transmission lines connecting each of said units to a receiving station.

70 14. The combination in a radio receiving system of a plurality of rows of directive receiving units, the rows being separated from one another by a substantial fraction of a wave length, means for changing the 75 directive curve of each unit, transmission lines connecting each of said units to a receiving station, and means at a receiving station for separately selecting from each unit a plurality of different currents of a desired 80 phase and intensity and impressing the currents so selected upon a corresponding number of sets of receiving apparatus.

15. The combination in a radio receiving system of a plurality of directive receiving units, a receiving set, a pair of artificial lines associated with each receiving unit and means for impressing upon the receiving set currents derived from all of said artificial lines. 85

90 16. The combination in a radio receiving system of a plurality of directive receiving units, a receiving set, a pair of artificial lines associated with each receiving unit, a series of coupling tubes equaling in number the 95 total number of artificial lines, the output circuits of said tubes being connected in parallel and associated with the receiving set, and individual connections from each of said artificial lines to the control circuit 100 of a coupling tube.

In witness whereof, I have hereunto set my hand this 20th day of November 1922.

EDWARD W. KELLOGG.
